UNITED STATES PATENT OFFICE

GEORGES HEBERLEIN, OF WATTWIL, SWITZERLAND, ASSIGNOR TO HEBERLEIN PATENT CORPORATION, OF NEW YORK, N. Y., A CORPORATION OF NEW YORK

MACHINE FOR PROCESSING FABRIC

Application filed November 4, 1926, Serial No. 146,187, and in Germany August 19, 1926.

My invention relates to a machine for processing fabrics, and more particularly to a machine for use in handling fabrics continuously or progressively in the processing or finishing 5 of the same with a suitable reagent or reagents. The invention in its particular embodiment herein described is especially useful in connection with the treatment of cotton fabric, or fabrics containing cotton fibres by 10 the use of a fibre-swelling agent, such for example as a suitable acid or alkali, in such manner as to produce a wool-like effect in the vegetable fibres, and for this purpose it is adapted to maintain the fabric in a loose or 15 unstretched condition throughout its treatment so as to permit a desired full shrinkage of the same.

The object of the invention is to provide a 20 simple, durable and efficient machine for use 20 in processing fabrics.

The invention consists in the novel features, 25 arrangements and combinations of parts hereinafter described according to the preferred embodiment of the invention, and the 25 invention will be more particularly pointed out in the appended claims.

The invention will be more readily understood from the following description taken in 30 connection with the accompanying drawing 30 illustrating by way of example the preferred embodiment of the invention.

The drawing illustrates a somewhat dia- 35 grammatic side elevation of a machine em- bodying the invention.

Referring to this drawing, 1 is a frame on 35 which are suitably mounted two substantial or powerful wringing rollers 2 geared and driven in any suitable manner (not shown).

These rollers are located above a tank 3 adapt- 40 ed to hold the agent which is to act upon the fabric and which may be maintained at any desired level in the tank. In connection with this tank there are provided a series of guide 45 rollers 4, one set near the bottom of the tank and one near the top of the tank, over which the web of fabric F is caused to travel. Suitably located above the wringing rollers 2 there is provided a reel 5 driven in any suitable manner and of any suitable construction 50 that will feed the web from the wringing

rollers without drawing it tight and which will deposit the web in loose folds or fanlike form onto a continuous or endless conveyer belt 6 adapted to pass over reels 7, 7'. These reels may be driven in any suitable manner 55 with provision for varying the speed of the conveyer belt. For the particular use here described, the speed is such that the loosely folded fabric will take from say 10 to 20 minutes to travel from one end of the conveyer to 60 the other during which period it is allowed to be acted upon by the retained reagent. This conveyer belt passes over suitably arranged guide rolls 8.

Above the outer end of the conveyer belt 6 is located another reel 9 driven in any suitable manner and at such speed as to feed the loosely folded fabric from the conveyer belt 6 onto a lower endless conveyer belt 10 driven by two reels or wheels 11, 11' and 70 passing over suitable guide rollers 12. The speed of the conveyer belt 10 and that of the reel 9 may be so chosen that the web of fabric will be deposited fanlike or in folded form 75 on the conveyer belt 10, or may be deposited without folds but loose and in unstretched condition. Both of the conveyer belts 6 and 10 may be of any suitable material such as ordinary cloth or impregnated fabric such as rubber cloth or the like, or of elastic wire 80 netting. A third conveyer belt 13 is provided beneath the last one and running in the opposite direction over reels or wheels 14, 14' and guided by guide rollers 15. In 85 this embodiment of the invention this last conveyer belt is driven at a faster speed than the other conveyer belts, so that the fabric delivered to this conveyer will be laid thereon flat and without folds so as to enable a proper washing of the same on this conveyer if desired, and for this purpose this conveyer 90 belt is preferably made of wire netting, and a series of sprinklers 16 (only one or two of which are shown) may be provided on both sides of the conveyer belt and extending throughout the entire length or any desired portion thereof and so positioned as to discharge the washing or cleansing fluid, such as water, against both sides of the moving web. 95 From this last conveyer belt the fabric may 100

be fed in any suitable manner to means for handling it for subsequent treatment, as for example it may be fed into a washing trough or washing machine or onto mechanism where it may be dried.

The means for driving the various parts in accordance with the speeds desired as stated above, I have shown diagrammatically in the drawing. The reel 5 is driven by a chain or belt 17 from a pulley 18 on the shaft of the wringer 2, the wringer is driven from an outside source of power, not shown. Mounted on the reel support is a pair of pulleys 19 equal about in diameter to 18 consequently having about the same speed. The second pulley of the pair 19 has a belt 20 running from it to a pulley 21 mounted on the shaft of the reel 7. This pulley 21 is slightly larger than the pulleys 19 so that the speed of the driven reel 7 is less than that of reel 5. The support for reel 7 has a pulley 22 mounted thereon driving through a chain 23 the reel 9 through a pair of pulleys 24. The latter pair is smaller in diameter than pulley 22 and therefore revolves at a greater speed. The second pulley of the pair 24 operates through a belt 25 to drive the pulley 26 mounted on the wheel 11. This pulley is slightly larger than the pulley 24 and drives the belt 10 at a slightly higher speed than that of the belt 6. A pulley 27 mounted on the reel 11' drives through a belt 28, a pulley 29 of larger diameter than 27 but smaller than reel 14'. The pulley 27 is slightly larger than the reel 11', so that the conveyer belt 13 has a higher speed than belt 10.

By arranging the plurality of conveyers two or more in superposed position and running them alternately in opposite directions, cost and space are economized.

When the machine is utilized for the purpose of treating fabrics with a swelling agent for the purpose of producing wool-like effects, the operation is as follows: The web F is fed over the guide rollers 4 through the swelling agent trough or tank 3 and thence between the powerful wringing rollers 2 which wring out the excess reagent, from whence the fabric is loosely fed by the feeding reel 5 onto the first conveyer belt 6 where it is deposited in fanlike form and allowed to travel along slowly, and from the other end of this belt it is lifted by the reel 9, deposited on the next conveyer belt 10, running in the opposite direction, where the web is also maintained in loose or slack condition, and then fed to the next and faster belt where it is deposited in flattened condition and washed by the sprayers 16, as stated, and from whence it is fed in any suitable manner.

Having thus described my invention, what I claim as new and desire to secure by Letters Patent, is:

65 1. In a machine of the character described,

the combination of means by which a web of fabric to be processed is subjected to a reagent, wringers for removing the excess reagent, a conveyer belt, means for driving the conveyer belt at a slower speed than the web as received, another conveyer for receiving said web from said first mentioned conveyer and means for driving it at a greater speed than the first conveyer so as to have the web deposited thereon in straightened out or flattened condition.

2. In a machine of the character described, the combination of means by which a web of fabric to be processed is subjected to a reagent, wringers for removing the excess reagent, a conveyer belt for receiving the squeezed out web, means for driving the conveyer belt at a slower speed than that of the web traveling from the wringers whereby the web is deposited on the conveyer loosely, means for feeding the web from said conveyer, a second conveyer and means for driving it at a greater speed than the first conveyer so as to have the web deposited thereon in straightened out or flattened condition, and means for washing said web while on said last conveyer.

3. In a machine of the character described, the combination of means by which a web of fabric to be processed is subjected to a reagent, wringers for removing the excess reagent, a conveyer belt for receiving the squeezed out web and for supporting it in loose condition, means for driving the conveyer belt at a slower speed than the web whereby the web is deposited on the conveyer loosely, means for feeding the web from said conveyer, a second conveyer having a conveyer belt composed of open material and means for driving it at a greater speed than the first conveyer so as to have the material deposited thereon in straightened out or flattened condition, means for feeding the material to the second mentioned conveyer, and means for washing said web while on said second mentioned conveyer.

4. In a machine of the character described, the combination of means by which a web of fabric to be processed is subjected to a reagent, wringers for removing the excess reagent, a conveyer belt for receiving the squeezed out web and for supporting it in loose condition, means above the conveyer for feeding the web from the wringers, means for driving the conveyer belt at a slower speed than the web whereby the web is deposited by gravity in loose folds upon the conveyer, a second conveyer below the first moving in the opposite direction from the first, means for feeding the web from the first conveyer onto the second conveyer, a third conveyer below the second and moving in the opposite direction, and means for moving it at a greater speed than the second, means for feeding the material from the sec-

ond to the third conveyer, and means for washing said web while on said third conveyer.

5. In a machine of the character described, the combination of means by which a web of fabric to be processed is subjected to a reagent, wringers for removing the excess reagent, a conveyer belt, means for driving the conveyer belt at a slower speed than the 10 web as received whereby the web is deposited on the conveyer in loose condition, means for feeding the web from the wringers to said conveyer so as to deposit the web on the conveyer loosely, means for feeding the web 15 from said conveyer, a conveyer below the first conveyer and means for driving it at a greater speed than the first conveyer so as to have the web deposited thereon in straightened out or flattened condition.

20 In testimony whereof I have signed my name to this specification.

GEORGES HEBERLEIN.
